UNITED STATES PATENT OFFICE

HAROLD B. LLOYD, OF SIOUX CITY, IOWA

NONSUBSTITUTING, SHIPPING, AND DISPENSING APPARATUS

Application filed July 22, 1931. Serial No. 552,333.

An object of my invention is to provide a suitable container for fluids with certain mechanical features which would render the container to be highly efficient from a mechanical standpoint.

Another object of my invention is to provide a container for fluids which will involve a minimum of parts, thereby creating such a device of the greatest possible simplicity.

10 A further object of my invention is to provide a container for fluids which is non-substituting, or in other words, to provide a container which can only be filled by the breaking of certain seals placed thereon by the firm or corporation whose product is specifically displayed on the container.

20 A further and important object of my invention is to provide a container in which the pumping means as made by the firm or corporation originally making the container cannot be applied to other containers without a great deal of labor and bother.

25 Another object of my invention is to provide such a pump made in a variety of ways so that non-substitution of these pumps on other containers will be quite readily achieved.

30 A further object of my invention is the combination of a non-substituting pump in the manner above described, together with other suitable and efficient means for evacuating the fluid from the container thereby creating a device of which character which would have the simplest and most desirable features incorporated therein.

35 With these and other objects in view, my invention consists in the construction, arrangement, and combination of the various parts of my device whereby the objects contemplated are attained as hereinafter more fully set forth, pointed out in my claims, and illustrated in the accompanying drawings, in which:

40 Figure 1 is a sectional view of the container taken through the center of the same showing the pump, discharge tube, and valve arrangement,

45 Figure 2 is a view of the lower part of the pump in one non-substituting form as applied to the container,

Figure 3 is another form of the same pump as applied to the container in a similar manner,

50 Figure 4 is an enlarged, sectional view of the valve, valve housing, and baffling arrangement,

Figure 5 is a view of the valve holder as applied to the lower plate in the container, which will be described later,

55 Figure 6 is a plan view of the valve on the same plate showing the plate mounted in one manner, and

Figure 7 is a view of the same showing the plate mounted in another manner, which will be described in the specifications.

60 I have used the reference characters 10 and 11 to denote the top and bottom of the container respectively, and 12 denotes the side walls of the container.

65 A bung 13, threaded internally, is welded 70 to the top of the container and projects downwardly. Into this bung 13 is threadedly secured the delivery tube 14 and through the top of the bung 13 is screwed the short pipe 15 which is threadably engaged as at 40 75 with the pump 41.

70 The lower end of the discharge tube 14 is threadably engaged with the valve housing 23-a which contains baffling flanges 16 80 which are solid portions of the housing 23-a itself.

75 A gasket 17 is provided beneath the flanges 18 of the said housing and rests upon the plate 19, which plate extends across the sump 20. The gasket 17 is secured against 85 leakage by means of the rivets 21 or which may be other suitable means for retaining a gasket under the proper pressure to enable the gasket to operate as a liquid-tight means.

80 On the plate 19 are mounted the ears 22, which are adapted to receive the thin flap valve 23, which valve closes the opening 24. The construction of the ears 22, which are made up of a single piece and bent as shown, 90 is shown attached to the plate 19, as in Figure 5.

95 The plate 19 can be fastened to the bottom end 11 of the container in one or more ways, as in Figures 6 and 7. In Figure 6, 100

the plate is shown spot-welded as at points 25 on its four corners, or as in Figure 7, with seam-welds as at 26, only in two corners. The plate 19 is made relatively long 5 over the sump 20 to provide a flexible means when connected with the discharge tube 14 so that in shipping or handling of the container, no undue strains will be developed between the upper and lower ends of the 10 container, 10 and 11 respectively. To accomplish the same results, the plate 19 is welded as shown in Figure 7 as at 26 thus creating a tendency for more resiliency between the rigid structures consisting of the 15 discharge tube and the valve housing, as applied between the ends 10 and 11 of the container.

It will be seen from the foregoing constructions that any strain of movements between the ends 10 and 11 of the container, either in a direction toward or away from each other will be absorbed or taken up by means of this plate structure. This is a very important feature in the construction of 20 such containers, since in many cases, discharge tubes fixed firmly to the top and bottom ends of such containers will break off in use, or set up harmful crystallization.

It will be seen from my structure that 30 this condition is remedied to a great extent and eliminates the necessity for supporting a valve housing with the valve housing hanging freely from one end, which condition might have harmful tendencies.

The flap valve 23 is urged against the opening 24 by means of the spring 39. An additional bung 27 is provided in the top 10 of the container. This bung is provided with a small set screw 28 which is 40 removed when pumping fluid from the container. The purpose of this is to admit air pressure within the container. The bung 27 is also provided with suitable seals and locking means, such as a key-pin which are 45 to be placed on the bung by the firm or corporation having its product displayed on the container.

In Figure 2, is shown a modified arrangement of the lower end of the pump 17. In 50 this case, the bung 29 threadably engages the discharge tube 14 in a similar manner to that shown in Figure 1. The upper face 30 of the bung 29 is smoothly machined.

The pump is attached to the bung 29 55 against the face 30 thereof by means of screws 31 passing through the flanges 32 of the pump, the screws 31 being threadably engaged with the tapped holes 33 in the bung 29.

A gasket 34 is tightened under pressure 60 against the lower face of the flange 32 and the face 30 of the bung 39 by the same means and at the same time.

In Figure 3, is shown a further modification 65 of the lower end of the pump as affixed

to the bung 29 and is slightly different in that a gasket 35 is placed within the recessant portion 36, the gasket being tightened by the screws 31 passing through the ears 37, which ears are an integral part of the 70 lower end of the pump.

It will be seen that these constructions offer a great advantage to the firm or corporation using their product in the container which has their display thereon. 75

For example, it would be comparatively impossible for a dealer to use a pump of this construction on a container containing a product other than that supplied by the original distributor without going to a great 80 deal of expense and labor.

In the form shown in Figure 1, the dealer would be compelled to remove the small pipe 15 and substitute a long pipe extending nearly to the bottom of the container and place 85 this arrangement down through an opening in the container. In this case, this would constitute an awkward arrangement, and the pump would probably hang at an angle unless supported in such an opening in a suitable manner which in itself would involve further expense and trouble. If the lower end of the pump were made as in Figures 90 2 and 3, and the dealer then tried to use on another container, he would be forced to 95 provide tapped holes and finished gasket surfaces in the bungs of such containers, which would require special machining, which ordinarily would not be attempted.

In shipping these containers, it will be 100 noted that the upper ends 38 of the inside threaded portion of the bungs will be left clear so that a suitable plug can be screwed in to prevent the outlet of any fluid within the container. 105

The sump 20 is incorporated in the bottom 11 of the container so that the maximum amount of fluid can be pumped therefrom.

The baffle plates 16 are adapted to prevent the insertion of any instrument, such 110 as a long wire, which might be used to try to manipulate the valve 23 so as to allow the influx of a product through the discharge tube 14, which product would not be authorized by the firm or corporation displayed on the container. 115

The baffle plates 16 are provided in overlapping relation so that under no possible circumstances can any instrument of this nature be twisted around so as to pass through the valve housing up to the valve. These baffles are solid and contain no holes therein which holes might allow the insertion of a wire or such means. 120

It will be seen that my invention incorporates a variety of desirable features. 125

An important feature is that of the non-substitution of a pump as supplied by a distributor. The pumps as ordinarily supplied for this purpose have extra thread faces for 130

screwing into the container, whereas, in my construction these threads are dispensed with and the provision of certain constructions eliminates convenient substitution unless a great deal of expense and labor is entered into.

Another important feature of my invention is the provision of a valve in a container at its lower end to allow the removal 10 of a fluid only through a discharge tube above said valve, which valve is protected from undesirable manipulation by suitable baffling means.

Another important feature of my invention 15 consists of the arrangement of its parts so that no undue strains will set up in any of its parts to cause crystallization or breakage.

Another feature of my invention is the 20 arrangement and combination of the parts so as to provide the simplest and most economical means of manufacture as applied to the art.

Some changes may be made in the 25 construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. In combination with a container, a discharge 30 tube within the container, a baffle plate housing attached to the lower end of the discharge tube, and a resilient plate attached to the baffle plate housing and to the container bottom.

2. In combination with a container, a discharge 35 tube within the container, a baffle plate housing attached to the lower end of the discharge tube, and a resilient plate attached to the baffle plate housing and to the container bottom, and a sump positioned beneath the baffle plate housing.

3. In combination with a container, a discharge 40 tube within the container, a housing including a plurality of integral overlapping plates attached to the lower end of the discharge tube, and a resilient plate attached to the housing arranged to provide flexibility between the upper and lower container ends.

4. In combination with a container, a discharge 45 tube within the container, a housing including a plurality of integral overlapping plates attached to the lower end of the discharge tube, and a resilient plate attached to the housing arranged to provide flexibility between the upper and lower container ends, said resilient plate having a port and valve means for closing the port.

5. In combination with a container, a discharge 50 tube within the container, a housing including a plurality of integral overlapping

plates attached to the lower end of the discharge tube, and a resilient plate attached to the housing arranged to provide flexibility between the upper and lower container ends, said resilient plate having a port and valve means for closing the port, comprising a relatively thin disc. 70

6. In combination with a container, a discharge 75 tube within the container, a housing including a plurality of integral overlapping plates attached to the lower end of the discharge tube, and a resilient plate attached to the housing arranged to provide flexibility between the upper and lower container ends, said resilient plate having a port, and valve means for closing the port, comprising a relatively thin disc, said disc being spring-urged against the port. 80

7. In combination with a container, a discharge 85 tube within the container, a housing including a plurality of integral overlapping plates attached to the lower end of the discharge tube, and a resilient plate attached to the housing arranged to provide flexibility between the upper and lower container ends, said resilient plate having a port, and valve means for closing the port, and a sump positioned beneath the port. 90

8. In a non-substituting container having 95 top and bottom walls and a side wall, a discharge pipe positioned substantially on the axis of the container and rigidly attached to the top wall thereof, a housing attached to the lower end of the discharge pipe, a valved port within the housing, an integral sump formed from the bottom of the container positioned beneath the valved port, and a lengthened plate overlapping the sump arranged to provide a resilient connection between the top and bottom walls of the container. 100

9. In a non-substituting container having 105 top and bottom walls and a side wall, a discharge pipe positioned substantially on the axis of the container and rigidly attached to the top wall thereof, a housing attached to the lower end of the discharge pipe, and including a plurality of overlapping baffle plates formed integrally therewith, a sump, a flexible plate attached to the bottom wall and positioned across the sump, a port hole in the flexible plate, a spring-urged valve pivotally secured above the port, said housing being arranged to inclose the port and the valve and attached to the flexible plate. 110

Signed at Sioux City, Iowa, this 13th day of July, 1931.

HAROLD B. LLOYD.
